(57) **CLAIM**

The ornamental design for an instant water heater, as shown and described.

DESCRIPTION

FIG. 1 is a perspective view of a first embodiment of an instant water heater in accordance with the present invention;

FIG. 2 is a front view of the instant water heater of FIG. 1; FIG. 3 is a first side view of the instant water heater of FIGS. 1 and 2;

FIG. 4 is a second side view of the instant water heater of FIGS. 1-3;

FIG. 5 is a top view of the instant water heater of FIGS. 1-4; and,

FIG. 6 is a bottom view of the instant water heater of FIGS. 1-5.

The broken line shown in the drawings are for the purpose of illustrating portions of the article and form no part of the claimed design.
